DESIGN FOR A LEG FOR AN ARTICLE OF FURNITURE

Antony K. Olach, Chicago, Ill.

Application June 3, 1940, Serial No. 92,785

Term of patent 7 years

To all whom it may concern:

Be it known that I, Antony K. Olach, a citizen of the United States, residing at Chicago, in the county of Cook and State of Illinois, have invented a new, original, and ornamental Design for a Leg for an Article of Furniture, of which the following is a specification, reference being had to the accompanying drawing, forming a part thereof.

Fig. 1 is a front elevational view of a leg for an article of furniture showing my new design; Fig. 2 is a side elevational view thereof; and Fig. 3 is a rear elevational view.

I claim:

The ornamental design for a leg for an article of furniture, substantially as shown.

ANTONY K. OLACH
